CLAIM

The ornamental design for a portion of a handheld device, substantially as shown and described.

DESCRIPTION

FIG. 1 is a perspective front view of a first embodiment of a handheld device.

FIG. 2 is a front view of the embodiment of FIG. 1.

FIG. 3 is a rear view of the embodiment of FIG. 1.

FIG. 4 is a left side view of the embodiment of FIG. 1.

FIG. 5 is a right side view of the embodiment of FIG. 1.

FIG. 6 is a bottom view of the embodiment of FIG. 1; and,

FIG. 7 is a top view of the embodiment of FIG. 1.

The broken lines immediately adjacent the shaded areas represent the bounds of the claimed design while all other broken lines are directed to environment and are for illustrative purposes only; the broken lines form no part of the claimed design.
